DEVICE FOR RETRIEVING OBJECTS

Ivor J. Gruenberg, Clarkston, Mich.

Application April 1, 1957, Serial No. 649,996

9 Claims. (Cl. 9—9)

The present invention relates to a device for retrieving liquid-immersed objects; and it deals, more particularly, with improvements in a device of this sort such as constitutes the subject matter of my copending application, Serial No. 557,801, filed January 6, 1956 now Letters Patent No. 2,892,198 of June 30, 1959.

It is an object of the invention to provide a retrieving device of this character attachable to a fishing rod, or other article which it is desired to buoy for recovery. The device comprises a hollow casing internally subdivided by an elastic envelope or bag into an inflating chamber, to which external liquid is admitted under predetermined hydrostatic pressure to chemically activate a gas generating inflating substance in that chamber, and an inflation-accommodating space at the opposite side of said bag, which last named space is releasably closed by a cap.

The invention affords, in this general combination disclosed in my above identified patent, improvements in regard to the positioning of the inflatable bag, the mode of insuring full scale chemical activation of the inflating substance to generate an ample volume of inflating gas, the mounting of this substance in the inflating chamber, provisions to facilitate and expedite the operation of the device by creating a velocity liquid flow head at one end thereof and an aspirative effect at the opposite end, etc.

More specifically, the invention has as an object the provision of an improved retrieving device of the above sort, in which the inflatable bag or envelope is positioned within the casing of the device to occupy, prior to inflation, a substantial portion of the volume of the inflating chamber in which the liquid-activatable substance is disposed. This has the effect of decreasing the amount of air in the inflating chamber which must be compressed upon activation of the inflating gas, and thus minimizes resistance to initial reversing collapse of the bag prior to its full inflation to buoy the device and the article to which it is attached.

By the same token, no limitation is imposed on the amount of water which may enter the inflating chamber, hence, an excess of water is assured to insure complete chemical reaction of the inflating substance.

It is a further specific object of the invention to provide a disintegrable container for the substance in the inflating chamber of the device which is to be chemically activated, thereby delaying slightly the reaction until ample water has been admitted to the chamber, as through a one-way hydrostatic pressure responsive valve. Thus, insurance is had that a premature and incomplete reaction will not take place, such as would have the effect of reclosing the valve under internal pressure in the chamber, yet insufficient in degree to properly inflate the bag.

Another specific object is to provide a device as described, in which a one-way hydrostatic pressure responsive valve controlling liquid intake to the inflating cham-

2

ber also serves as a holder for the chemical inflating substance, or the disintegrable container for that substance.

In accordance with a still more specific improvement of the invention, the valve in question is provided with an integral, button type extension, as a convenience in the mounting of the valve on the casing of the device.

Yet another object is to provide this type of retrieving device, in which the valve thereof is disposed at the lower end of the device, in its gravity descent, and in which provision is made for the intake of liquid under a predetermined hydrostatic pressure and assisted by a velocity head acting on the valve.

A still further object is to provide a retrieving device as referred to in the preceding paragraph, in which the opposite end of the casing is apertured to provide an opening to its exterior which is of capillary size of bore and communicates with the space on the side of the inflation bag opposite the inflating chamber of the casing. As described in my above identified patent, the pressures on opposite sides of the bag are thus equalized under all conditions, and the expulsion of air from the space in question through the capillary openings is facilitated, thus assisting the inflation of the bag. Another and more limited object is to provide such a device, in which the capillary opening is formed in a cap releasably engaged with the casing for displacement therefrom upon inflation of the bag; and, more particularly, in which this opening is formed in the end of the cap opposite the valve of the device, being surrounded by a projecting wall to the end that an aspirative action is induced in the descent of the device to further assist in the expulsion of air through the capillary opening.

In general, the invention has as its most important object the provision of a retrieving device in which the above described features all combine to afford maximum compactness, maximum economy in cost, and maximum effectiveness in its intended buoyant function.

The foregoing as well as other objects will be made more apparent as this description proceeds, especially when considered in connection with the accompanying drawings, wherein:

Fig. 1 is a view in vertical axial section through a retrieving device in accordance with one embodiment of the invention;

Fig. 2 is a bottom plan view of that device;

Fig. 3 is a view in section similar to Fig. 1 of a modified embodiment; and

Fig. 4 is a fragmentary view illustrating a suggested manner of removably attaching the device to a fishing rod, as a typical object most commonly to be retrieved by the device.

Referring to Figs. 1 and 2, in one embodiment of the improvement the device 10 comprises an elongated cylindrical body or casing 11 of rigid material having a lower end wall 12 provided with apertures or ports 13 of substantial size, and of the outline depicted in Fig. 2, for the admission under a predetermined hydrostatic head of water or other liquid in which a device is immersed.

Fig. 4 of the drawings shows a suggested mode of removably attaching the device 10 to a fishing rod, as by conventional adhesive tape 14 binding the same to the rod, designated 15, and permitting convenient removal and attachment of the device by the user to another of his rods. In this regard, it will be perceived that the device 10 may be fabricated sufficiently compact and light in weight, due to the improvements, that it does not unduly bulk the rod or become a source of distraction or annoyance to the fisherman.

Again referring to Fig. 1, the reference numeral 16 generally designates a one-way hydrostatic pressure sensitive valve of the disk type applied to the casing wall 12 in a novel manner. Valve 16 is of molded natural or

synthetic rubber, a resilient plastic compound or the like, and presents an annular radial sealing flange 17 of considerable flexibility which normally seats over the intake ports 13 until the predetermined hydrostatic pressure arises in the descent of the device 10. Valve 16 is provided with an integral projecting, enlarged head button 18 at the center of its lower surface; and the casing end wall 12 has a central aperture 19 into which this button is drawn from the interior of the casing, its enlarged head then snapping into place externally of the wall to hold the valve to the casing. Upon completion of this simple assembly procedure, an excess length of the button 18 (which may be gripped by pliers to pull the valve into place, this excess being shown in dotted line and designated 20) is snipped off.

The reference numeral 21 designates a container filled or partially filled with a chemical inflating agent, as hereinafter referred to; and in accordance with the invention the valve 16 provides a holder for this container. To this end, the valve is molded to provide an axially extending annular wall 22 at its center, which wall defines a well in which the container 21, shown as a cylindrical tube, is inserted and elastically gripped.

It is to be noted that, with the device 10 applied to the rod 15 in the manner shown in Fig. 4, it will descend gravitationally in the upright position shown in Fig. 2 of the drawing. Thus, in positioning the intake ports 13 in the bottom end wall 12, a velocity head is exerted on valve 16 to assist hydrostatic pressure in uncovering the ports 13. This action is complemented by an aspirative action at the opposite end of the device, as will be described.

The container 21 is firmly supported by the valve well 22 in a lower inflating chamber 24 within the casing 11. Container 21 is, in accordance with the invention, fabricated of a liquid-disintegrable material, for example, such as a thin cellulosic tissue, as cigarette paper, or a water soluble material, such as a gelatin-like compound, or the like. It is charged with an appropriate chemical substance which, when activated by water or other liquid generates a copious quantity of gas. Typical substances are the aluminum carbide, calcium carbide, sodium bicarbonate, together with a crystalline acid, mentioned in my above mentioned patent. At a predetermined level, preferably in substantial axial spacing from the intake ports 13, the container 21 is provided with a plurality of orifices 25 for the direct admission of liquid to activate the chemical.

Thus, the disintegrable or liquid soluble container 21 will delay the chemical interaction with liquid entering the inflating chamber 24 until it has reached the apertures 25. This insures the admission of an excess quantity of water, preferably over and above the quantity required for complete activation of the contained chemical. As activation commences and continues, the material of container 21 will disintegrate sufficiently or dissolve to continue the gas-evolving reaction at a rapid rate. Insurance is had that the desired excess of liquid is admitted, without a premature reaction such as might generate only a slight quantity of gas, but sufficient to produce enough pressure in chamber 24 to re-close valve 16, or to at best occasion a hunting or fluttering effect at the valve sealing flange 17.

The reference numeral 26 designates an inflatable bag or envelope of natural or synthetic rubber in a thin wall section. An upper open end 27 of the bag is appropriately secured, as by bonding, glued adhesion, or mechanical means, in sealed relation to the inner surface of the casing 11, at the end of that casing opposite the valve provisions described above. It is inflated to the dotted line buoyant position of Fig. 1 by the generated gas, as will be understood.

In its normal collapsed position bag or envelope 26 extends a substantial axial distance from the open end 27 toward the container 21, being sectionally cross-

sectioned to conform with the internal wall of casing 11, and has a closed lower end wall 28 closely adjacent the chemical container.

It is thus seen that the bag 26 in its normal, uninflated condition, and being reversibly orientated in reference to the container 21 and inflating chamber 24, occupies a substantial portion of that chamber, to the exclusion of air which would otherwise be present. This minimizes the volume of such air which needs to be compressed prior to generation of gas, thereby assisting the hydrostatic-velocity head pressure actuation of the valve 16 and the admission of copious water to chamber 24.

Outwardly of the thickened and sealed end 27 of bag 26, the casing is releasably closed by a suitable domed cap 29, frictionally held to the casing and ejected therefrom upon inflation of bag 26. In accordance with the invention, and as in my patent identified above, the cap 29 has at its axial center a small opening 30 which is of capillary size of bore, i.e., sufficiently small to prevent entry of liquid to the space 31 within the cap, due to capillarity, but enabling the expulsion of air from the space 31 and the space within the inverted bag 26 communicating therewith.

The capillary opening 30 is an important factor in the operation of the device, as pointed out in my previous application, equalizing air pressures on opposite sides of the bag 26 under all atmospheric conditions and permitting free and unresisted expulsion of air from space 31 as the bag collapses upwardly. However, in accordance with the invention this expulsion is further assisted by the provision of an annular external wall 32 on the axial upper nose of the cap, providing a recess or well 33 to create an area of lower pressure surrounding the capillary opening 30.

Thus as the device 10 descends, in the upright orientation of Fig. 1, the wall 32 causes an aspirative suction effect in the recess 33, thus promoting outward flow of air through the opening 30. The combined velocity action at the valve intake ports 13 and aspirative action at the recess 33 are highly effective in promoting a copious filling of inflating chamber 24 with water, once a predetermined hydrostatic pressure is in effect; and the quick and copious entry of the liquid to the chamber 24 is of essential importance in the operation of the improved device.

It will be recognized that quick and ample filling is promoted also by the inversion of the bag 26 to occupy space otherwise occupied by air to be compressed, as well as by the employment of a disintegrable or soluble delay action container 21 for the chemical gasifying agent. These features function to prevent premature closure of valve 16.

An alternative form of the device is shown in Fig. 3, being generally designated 35. It is identical with the embodiment of Figs. 1 and 2 in all respects save its valving provisions. Accordingly, corresponding parts common to the two forms are designated by corresponding reference numerals and further description thereof will be dispensed with.

As illustrated in Fig. 3, a valve 36 of rubber or resilient plastic or like flexible material is formed in a generally cupped-shaped cross-section, and is telescopingly inserted into the bottom of the casing, its bottom base wall 37 abutting the bottom end wall 12 of the casing, which is in this case simply apertured centrally at 38 to facilitate the insertion of the valve by bleeding air.

The casing 11 is, in the form of Fig. 3, provided with an annular series of liquid entry ports 39, which are normally closed by the annular upstanding wall 40 of valve 36, this wall axially overlapping the ports and being feathered at its free edge 41 for increased flexibility. The resilient valve wall 40 will yield radially inwardly under predetermined hydrostatic pressure, assisted in some degree by a velocity pressure head as described above, to admit liquid to the inflating chamber 24.

Cup valve 36 is provided with an integral upstanding annular wall 42 surrounding its axis in the interior thereof, and this wall elastically embraces the container 21 for the chemical inflating agent, as in the embodiment of Fig. 1.

The arrangement of parts on the device 35 is such that they have an integrated action as in the first form, to the end of compacting the over-all structure by insuring a copious generation of gas in a relatively small confining space; this, in turn, being accomplished by delaying the chemical gasification process until an adequate liquid has been received to insure its completion and by thereafter insuring minimum opposition to be exerted against the inflationary pressure so generated. In this way, resistance to the inflowing water at the predetermined hydrostatic pressure is minimized.

What I claim as my invention is:

1. A device for retrieving liquid-immersed articles comprising a casing attachable to the article and provided with valve means responsive to predetermined external hydrostatic pressure to admit liquid to the interior of the casing, an elongated open-ended bag sealed at its open end zone to the casing and extending a substantial distance axially inwardly from said zone toward a closed end thereof, said bag occupying a substantial portion of the interior volume of said casing and subdividing the same into an inflating chamber communicable with said exterior by said valve means and an outer space of substantial volume located radially inwardly of said sealed zone and extending substantially therefrom in an axial direction, said casing having an aperture of capillary size of bore opening to said outer space, and expanding means in said inflating chamber actuated by liquid admitted by said valve means to axially reverse said bag and inflate the latter.

2. A device for retrieving liquid-immersed articles comprising a casing attachable to the article and provided with valve means responsive to predetermined external hydrostatic pressure to admit liquid to the interior of the casing, an elongated open-ended bag sealed at its open end zone to the casing and extending a substantial distance axially inwardly from said zone toward a closed end thereof, said bag occupying a substantial portion of the interior volume of said casing and subdividing the same into an inflating chamber communicable with said exterior by said valve means and an outer space of substantial volume located radially inwardly of said sealed zone and extending substantially therefrom in an axial direction, said casing having an aperture of capillary size of bore opening to said outer space, and expanding means in said inflating chamber actuated by liquid admitted by said valve means to axially reverse said bag and inflate the latter, said casing including a cap releasably applied to the axial end thereof remote from said inflating chamber and closing said outer space, in which cap said aperture is formed.

3. A device for retrieving liquid-immersed articles comprising a casing attachable to the article and provided with valve means responsive to predetermined external hydrostatic pressure to admit liquid to the interior of the casing, an elongated open-ended bag sealed at its open end zone to the casing and extending a substantial distance axially inwardly from said zone toward a closed end thereof, said casing having an inflating chamber in said interior thereof and an aperture of capillary size of bore opening to an outer space therein on the side of said bag opposite said inflating chamber and sealed from the latter at said zone, and expanding means in said inflating chamber actuated by liquid admitted by said valve means to axially reverse said bag and inflate the latter, said casing including a cap releasably applied to the axial end thereof remote from said inflating chamber and closing said outer space, in which cap said aperture is formed, said cap having an end recess surrounding said aperture.

4. A device for retrieving liquid-immersed articles comprising an elongated axially extending casing attachable to the article and provided with a one-way valve responsive to predetermined external hydrostatic pressure to admit liquid to a portion of the casing interior, an inflatable bag dividing said first portion from the remaining portion of said interior, said bag having sealed engagement at an open end thereof with the casing adjacent an axial end of said remaining portion to separate said portions and extending toward a closed end located well within said first portion and a substantial distance from said open end, said casing being provided with a valve port controlled by said valve, which port opens to said first interior portion in an axial end zone of the device subject to a liquid velocity head in the gravity descent of the device, said casing having an aperture of capillary size of bore opening to said remaining interior portion at an opposite axial end of the device, and expanding means in said first interior portion adapted to be actuated by liquid admitted by said valve to collapse said bag.

5. A device for retrieving liquid immersed articles comprising a casing attachable to the article and provided with a one-way valve responsive to predetermined external hydrostatic pressure to admit liquid to a portion of the casing interior, an elongated inflatable bag normally occupying a substantial further portion of said interior and displacing a substantial volume of air therein, said bag having sealed engagement at an open end thereof with the casing to subdivide said portions and extending toward a closed end a substantial distance from its seal, said casing being provided with a valve port controlled by said valve, which port opens to said first interior portion in an end zone of the device subject to a liquid velocity head in the gravity descent of the device, said casing having an aperture of capillary size of bore opening to said further interior portion at an opposite end of the device, and expanding means in said first interior portion adapted to be actuated by liquid admitted by said valve to reverse and collapse said bag.

6. A device for retrieving liquid immersed articles comprising a casing attachable to the article and provided with a one-way valve responsive to predetermined external hydrostatic pressure to admit liquid to a portion of the casing interior, an inflatable bag dividing said first portion from a further portion of said interior, said bag having sealed engagement at an open end thereof with the casing to subdivide said portions and extending toward a closed end a substantial distance from its seal, said casing being provided with a valve port controlled by said valve, which port opens to said first interior portion in an end zone of the device subject to a liquid velocity head in the gravity descent of the device, said casing having an aperture of capillary size of bore opening to said further interior portion at an opposite end of the device, and expanding means in said first interior portion adapted to be actuated by liquid admitted by said valve to collapse said bag, said casing being provided with a recess at said last named end thereof surrounding said aperture to occasion an aspirative effect thereon in the descent of the device.

7. A device for retrieving liquid immersed articles comprising a casing attachable to the article and provided with a one-way valve responsive to predetermined external hydrostatic pressure to admit liquid to a portion of the casing interior, an elongated inflatable bag normally occupying a substantial further portion of said interior and displacing a substantial volume of air therein, said bag having sealed engagement at an open end thereof with the casing to subdivide said portions and extending toward a closed end a substantial distance from its seal, said casing being provided with a valve port controlled by said valve, which port opens to said first interior portion in an end zone of the device subject to a liquid velocity head in the gravity descent of the device,

said casing having an aperture of capillary size of bore opening to said further interior portion at an opposite end of the device, and expanding means in said first interior portion adapted to be actuated by liquid admitted by said valve to reverse and inflate said bag, said casing being provided with a recess at said last named end thereof of surrounding said aperture to occasion an aspirative effect thereon in the descent of the device.

8. A device for retrieving liquid immersed articles comprising a casing attachable to the article and provided with a one-way valve responsive to predetermined external hydrostatic pressure to admit liquid to a portion of the casing interior, an inflatable bag dividing said first portion from a further portion of said interior, said bag having sealed engagement at an open end thereof with the casing to subdivide said portions and extending toward a closed end a substantial distance from its seal, said casing being provided with a valve port controlled by said valve, which port opens to said first interior portion in an end zone of the device subject to a liquid velocity head in the gravity descent of the device, said casing having an aperture of capillary size of bore opening to said further

5 interior portion at an opposite end of the device, and expanding means in said first interior portion adapted to be actuated by liquid admitted by said valve to inflate said bag, said casing being provided with a cap at said last named end thereof releasably closing said further portion, said cap having a recess surrounding said aperture to occasion an aspirative effect thereon in the descent of the device.

9. A device in accordance with claim 8, in which said expanding means is a substance activatable by liquid to produce an inflating gas, said substance being enclosed by a protective member subject to delayed penetration by the liquid.
